UNITED STATES PATENT OFFICE

GUY R. COYNE, OF MILWAUKEE, WISCONSIN, ASSIGNOR TO UNITED SHOE MACHINERY CORPORATION, OF PATERSON, NEW JERSEY, A CORPORATION OF NEW JERSEY

SOLE LAYING

Application filed October 4, 1926. Serial No. 139,437.

This invention relates to the attachment of soles to shoes and is illustrated herein with reference to the laying of soles in the manufacture of McKay shoes.

In performing the McKay sole laying operation, a channeled and grooved outsole is positioned by the operative in the proper relation to the insole and upper of a lasted shoe. The operative then usually presents the work to the nozzle of a staple-inserting machine, inserting a staple at each end of the tip line of the sole, a pair of staples at the ball line, a pair of staples in the shank, and two or three staples in the heel-seat. Prior to my invention, it was customary to insert these staples with their bars positioned transversely of the groove, and, accordingly, it has frequently happened that the bars of the staples caught upon the barb of the needle of the McKay stitcher as the needle was withdrawn from the work during the subsequent stitching operation. This often resulted in breaking the needle and in breaking or damaging the thread.

As the characteristic McKay seam is a chain-stitch seam, it is necessary that it be continuous from one end to the other in order to maintain its maximum strength. Accordingly such damage to the thread

weakens the seam in a most undesirable way. It is an object of the present invention to obviate so far as possible the breaking of needles and the damage of the thread in the through-and-through stitching of outsoles to lasted insoles and shoe uppers. This I have accomplished by positioning such of the staples as are near the line of stitching with their bars upon the shoulder of the groove in which the stitching lies and parallel to the groove instead of transversely of the groove. With the staples thus positioned, the bars will not catch upon the barb of the needle. If an occasional staple should be positioned so close to the groove as to be struck by the needle of the stitcher, the staple may be nicked or even cut in half by the needle, but while the needle is passing into the sole the thread is protected by the barb of the needle, and the bar of the staple is not in a position to

interfere with the withdrawing of the needle. Thus the breakage of needles and damage to the thread are very much reduced.

In its different aspects, my invention comprises both an improved method of manufacturing shoes and a shoe characterized by the preliminary attachment of a grooved and channeled sole by staples located in the shoulder of the groove and adjacent to the groove with the bars of the staples substantially parallel to the groove.

While the invention is described herein with reference to the manufacture of McKay shoes, it should be understood that this is merely for the purpose of illustration and that in various of its aspects it is not limited thereto.

In the drawings,

Fig. 1 is a perspective view of a McKay shoe in process of manufacture; and

Fig. 2 is a sectional view on a larger scale showing the relation of the staple to the groove and channel of the outsole of the shoe.

In manufacturing shoes in accordance with my invention, the shoe upper 10 is lasted to an insole 12 upon a last 14 having an iron bottom 16 in accordance with a usual practice. An outsole 18 having a channel 20 extending from the heel-breast line, through the shank, about the forepart of the shoe, and back to the heel-breast line upon the other side of the shoe, is then preliminarily attached to the lasted shoe upper and insole. The outsole is provided with a stitch receiving groove 22 located in the channel parallel to the edge of the shoe, there being a shoulder 24 formed by the bottom of the channel 20 and a wall of the groove 22. A flap 26 is formed during the channeling operation and later is laid to cover the sole attaching means. The operative, after properly positioning the outsole relatively to the lasted shoe upper and insole, attaches it preliminarily thereto by a plurality of staples 28 located, preferably and as illustrated, at the tip line, the ball line, and in the shank. These staples are inserted through the shoulder 24 of the groove closely adjacent to the groove with

their bars extending substantially parallel to the groove, both legs of each staple being clenched against the iron bottom of the last. Other staples 30 are then driven to hold the heel-seat portion of the outsole to the insole and upper.

If the shoe has a sufficiently pointed toe so that it is not desired to continue the stitching by which the sole is to be attached around the toe, then a group of staples 32 is inserted around the toe permanently to hold the toe portion of the outsole to the lasted upper and insole. The positioning of the outsole and the driving of these various staples constitute the sole laying operation.

After the sole has been laid, the last is pulled from the shoe and the outsole is permanently attached to the upper and insole by through-and-through stitching 34, extending either from the heel breast line forwardly around the toe and back to the heel breast line or, if the toe of the outsole is attached only by staples as indicated in Fig. 1, from the heel breast line to the tip line on both sides of the shoe. If the needle 36 of the stitcher should descend in close proximity to the bar of one of the staples, its barb cannot catch upon the bar of the staple as the needle is withdrawn, as it might do and often does when the bars of the staples are positioned transversely of the groove. Accordingly the possibility of the breaking of the needle or damaging the thread is minimized, and a strong seam results.

Having described my invention, what I claim as new and desire to secure by Letters Patent of the United States is:

1. That improvement in methods of sole laying which comprises preliminarily attaching a channeled and grooved outsole to the lasted upper and insole of a shoe by inserting staples in the shoulder of the groove of the outsole and adjacent to the groove with the bars of the staples substantially parallel to the groove, and clenching both legs of each staple.

2. That improvement in methods of manufacturing shoes comprising preliminarily attaching an outsole, channeled and grooved for stitching, to a lasted shoe upper and insole by staples located in the shoulder of the groove and adjacent to the groove with the bars of the staples substantially parallel to the groove and permanently attaching the sole to the lasted shoe upper and insole by through-and-through stitching located in the groove of the outsole.

3. A shoe having a grooved and channeled outsole attached to the insole and upper of the shoe by staples inserted in the shoulder of the groove adjacent to the groove with their bars substantially parallel to the

groove and by through-and-through stitching located in the groove.

In testimony whereof I have signed my name to this specification.

GUY R. COYNE.
